Application October 29, 1956, Serial No. 43,558

Term of patent 14 years

(Cl. D58—8)

FIG. 1

FIG. 2

FIG. 3

Fig. 1 is a fragmentary side elevational view of a vacuum bottle, showing my new design;

Fig. 2 is a side elevational view thereof with the vacuum bottle turned ninety degrees from the position shown in Fig. 1; and

Fig. 3 is a top plan view thereof.

The dominant features of my design reside in the portions shown in full lines.

I claim:

The ornamental design for a vacuum bottle, as shown and described.
